CLAIM

The ornamental design for a ratchet socket of a skateboard wrench as shown and described.

DESCRIPTION

FIG. 1 is a front top right perspective view of a ratchet socket of a skateboard wrench showing my new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a front top left perspective view thereof;

FIG. 9 is a bottom left perspective view thereof; and

FIG. 10 is a perspective view which the design is mounted in the skateboard wrench in a condition of use thereof; and,

FIG. 11 is a bottom perspective view which the design is mounted in the skateboard wrench in a condition of use thereof.

The broken lines of FIGS. 10 and 11 are included for the purpose of illustrating environmental structure and forms no part of the claimed design.

1 Claim, 10 Drawing Sheets
